UNITED STATES PATENT OFFICE.

NOAH N. NEHER AND JOHN F. NEHER, OF TOPEKA, KANSAS.

DOOR STOP AND HOLDER.

SPECIFICATION forming part of Letters Patent No. 739,906, dated September 29, 1903.

Application filed November 28, 1902. Serial No. 133,040. (No model.)

To all whom it may concern:

Be it known that we, NOAH N. NEHER and JOHN F. NEHER, citizens of the United States, residing at Topeka, in the county of Shawnee, 5 and State of Kansas, have invented new and useful Improvements in Door Stops or Holders, of which the following is a specification.

This invention relates to door stops or holders; and the primary object thereof is to 10 provide positively-operating means for retaining a door against movement at determined intervals.

The invention consists in the construction and arrangement of the several parts, which 15 will be more fully hereinafter described and claimed.

In the drawings, Figure 1 is a transverse vertical section through a part of a door and the improved stop or holder shown applied thereto. Fig. 2 is a front elevation of a portion of a door, showing the improved stop applied thereto and in engagement with the floor. Fig. 3 is an enlarged horizontal section taken in the plane of the line 3 3, Fig. 1. 20 Fig. 4 is a similar section taken in the plane of the line 4 4, Fig. 1. Fig. 5 is a similar section taken in the plane of the line 5 5, Fig. 1.

Similar numerals of reference are employed to indicate corresponding parts in the several 25 views.

The numeral 1 designates an elongated plate which serves as a main support and attaching means for the improved stop or holder and is secured to a door or other swinging object 2. 30 The plate intermediate its ends is provided with a laterally-projecting lug 3 and below the lug 3 a suitable distance with a projection 4. A bolt-casing 5 is secured to the plate 1 through the medium of ears 6, projected 35 through openings 6^a in the said plate 1 and bent against the rear face of the latter, as clearly shown by Figs. 3 and 4. The casing 5 has a slot 7 therein at an intermediate point, through which a dog 8 movably projects, the 40 said dog being substantially U-shaped and pivoted to the sides of the casing. A bolt 9 is slidingly mounted in the casing 5 and has a socket at its lower extremity in which is seated a resilient pad or buffer 10. The bolt 45 9 is hollow, and therein is disposed a spring 11, having one terminal in contact with the bottom of the bolt above the socket and the

opposite terminal engaging the lower end of a tube 12, movably mounted within the bolt 9 and embraced by the side flanges 13 and 14 of the latter, said flanges being connected at their upper extremities by a cross-bar 15. The tube 12 is formed with vertically-disposed side openings or slots 16 and 17, through which projects a limiting-pin 18, terminally secured in the side flanges of the bolt, whereby the tube 12 will be held against displacement, but permitted to slide relatively to the bolt. The front surface of the tube 12 is corrugated or serrated to form teeth for engagement by the adjacent edge of the dog 8, movable thereover, and between the lug 3 and the upper end of the tube 12 a spring 19 is interposed to normally hold the casing 5 and bolt 9 disposed therein out of contact with the floor. The upward movement of the bolt will be limited by the projection 4, which will be engaged by the upper edge of the bolt when the latter is in its raised position.

The improved stop or holder will be normally held in elevated position; but when it is desired to hold the door to which it is applied ajar or open at any desired point the operator exerts a sufficient downward pressure on a flange 20 or top of the tube 12 to 50 overcome the resistance of the spring 19 and permit the dog 8 to engage a portion of the irregular surface of the said tube to hold the bolt and tube 12 in lowered position and cause the resilient cushion 10 at the lower end of the bolt to engage the floor. This cushion will be made, preferably, of rubber or some similar material, so as to readily adhere to the floor and prevent accidental movement of the door held thereby. The spring 11 will 55 force the bolt against the floor and permit a slight play of the latter in view of the provision of the slots 16 and 17 and the pin 18. When it is desired to release the pad or cushion 10 from engagement with the floor, the operator will depress the dog 8 far enough to throw the engaging edge of the latter out of contact with the irregular surface of the tube 12, and thus allow the spring 19 to exert its force on the tube 12 and raise the latter, as 60 well as the bolt 9.

By the construction set forth the improved stop or holder can be adjusted to accommodate any depression or irregularity of dis-

tance between the bottom edge of the door and the floor. This is a material advantage, inasmuch as a floor frequently becomes warped or worn, and to compensate for such inequalities the stop or holder can be readily adjusted. It will be apparent that the improved device is capable of easy manipulation and can be operated by the foot, thus obviating the necessity of bending the body for this purpose.

Having thus fully described the invention, what is claimed as new is—

In a door-stop, the combination with a plate having a horizontally-arranged lug intermediate its ends, of a projection below the lug, a casing carried by the plate and provided with a slot, a bolt vertically sliding in the case, said bolt being hollow and having elongated slots in its side walls, a pin projecting through the side of the casing and through

the slots in the bolt, a spring interposed between the end of the bolt and the pin, a tube telescopically arranged on the bolt, a spring interposed between the lug and the top of the tube, and a pivoted dog carried by the casing and having an engaging edge projecting through the slot in the tube, said edge positively engaging the surface of the tube for the purpose set forth. 25

In testimony whereof we affix our signatures in presence of witnesses. 30
